UNITED STATES PATENT OFFICE.

HARRY E. DOANE, OF CINCINNATI, OHIO, ASSIGNOR TO THE J. D. RANDALL COMPANY,
OF CINCINNATI, OHIO, A CORPORATION OF OHIO.

HORSE-COLLAR-STUFFING MACHINE.

1,069,769.

Specification of Letters Patent. Patented Aug. 12, 1913.

Application filed November 29, 1912. Serial No. 733,949.

To all whom it may concern:

Be it known that I, HARRY E. DOANE, a citizen of the United States of America, and resident of Cincinnati, county of Hamilton, 5 and State of Ohio, have invented certain new and useful Improvements in Horse-Collar-Stuffing Machines, of which the following is a specification.

My invention relates to horse collar 10 stuffing machines of the class which has a reciprocating feed rod for feeding straw from a receptacle or hopper through a tube into the easing of a horse collar, and in which a rotating member is provided for 15 rotating the straw in the hopper, above the reciprocating feed rod.

The object of my invention is to provide 20 a rotating member for engaging the straw near the bottom of the hopper, to a depth such as to present a maximum amount of 25 the strands of the straw in a position at right angles to the travel of the feed rod, and which does not obstruct the downward travel of the straw to the feed rod.

In the accompanying drawings, Figure 1 30 is a central vertical sectional view of as much of a horse collar stuffing machine as is necessary to illustrate my invention, parts of the hopper being shown broken out, for clearness of illustrating. Fig. 2 is a plan view of my agitating ring.

The machine embodying my invention 35 comprises a cylindrical hopper A for holding the straw, a base B upon which the hopper is mounted, a feed rod D which reciprocates in a diametrical slot in the bottom of the base beneath the hopper, and an agitating ring C, which is located in a recess formed in the base beneath the hopper, and 40 is provided with means for engaging the straw, so as to rotate it above the feed rod and present the strands of the straw in a position such that the teeth of the feed rod will readily engage them and carry them 45 forward into the feed tube E.

Base B is a shallow cylindrical box, whose 50 vertical flange δ has a circular recess b' upon its interior. Hopper A has near its bottom a horizontal circular flange a , which 55 rests upon the flange b , and is secured thereto by bolts a' . Flange a may be secured to the hopper by rivets a'' ; or may be formed integral therewith. The flange a projects inward above recess b' .

Ring C has a downwardly projecting an-

nular lug c , which fits into an annular groove in the base B. Ring C has external gear teeth c' , which are engaged by a pinion F, which may be rotated by any suitable means for imparting rotation to the agitating ring C. Upon the interior of the ring C, vertical blades G are secured. Blades G have their width disposed radially and have their upper edges g beveled. The edges g' of the blades are adjacent to the inner walls 60 of the hopper A. The blades may be secured to the ring C by bolts g'' .

In operation: Straw being placed in the hopper A in a tangled mass, has placed upon top of it a disk H, whose weight presses the straw toward the feed rod. Rotation being imparted to the ring C, by rotating the pinion F, the blades G engage the mass of straw at the bottom of the hopper for a sufficient distance above the feed rod, to insure the presentation of a sufficient number of strands of straw at right angles to the path of travel of the feed rod, such that a maximum number of straws will be engaged by each of the teeth of the feed rod, upon each forward stroke thereof, and be carried by them into the feed tube. The blades G being disposed vertically, form no obstruction upon which the strands of straw may become caught in their downward passage toward the feed rod.

What I claim is:

1. The combination in a horse collar stuffing machine of a hopper, a ring below the hopper, vertical blades within the bottom of the hopper standing adjacent to the inner walls of the hopper and secured to the ring, means for rotating the ring, and a feed rod below the ring and adapted to be reciprocated.

2. The combination in a horse collar stuffing machine of a shallow base having an annular recess formed upon its inner wall, a hopper mounted upon the base above the recess, a ring seated in the recess, vertical blades secured to the ring and projecting upward adjacent to the inner walls of the hopper, a feed rod below the ring and adapted to be reciprocated, and means for rotating the ring.

3. The combination in a horse collar stuffing machine of a shallow base having an annular recess formed upon its inner wall, a hopper mounted upon the base above the recess, a ring seated in the recess, vertical

blades secured to the ring and projecting upward adjacent to the inner walls of the hopper, the width of the blades being disposed radially, a feed rod below the ring and adapted to be reciprocated, and means for rotating the ring.

In testimony whereof, I have hereunto

subscribed my name this 26th day of November, 1912.

HARRY E. DOANE.
